(57) **CLAIM**

The ornamental design for a medical device stand docking head, as shown and described.

DESCRIPTION

This application is related to copending U.S. application Ser. No. 29/357,526, filed concurrently herewith and entitled “Medical Device Stand Docking Station,” and U.S. patent application Ser. No. 12/616,642, filed Nov. 11, 2009 and entitled “Charging Station for Cordless Ultrasound Cart,” the disclosures of which are incorporated herein by reference.

FIG. 1 depicts a perspective view of a medical device stand docking head of our new design, with the point of connection for interfacing with a medical device stand docking station, the switch interlock, and the rear portion for attaching to a

medical device stand shown in phantom for environmental purposes only and forming no part of the claimed embodiment;

FIG. 2 is a front elevation view of the medical device stand docking head of FIG. 1, with the point of connection for interfacing with a medical device stand docking station, the switch interlock, and the rear portion for attaching to a medical device stand shown in phantom for environmental purposes only and forming no part of the claimed embodiment;

FIG. 3 is a rear elevation view of the medical device stand docking head of FIG. 1, with the point of connection for interfacing with a medical device stand docking station and the rear portion for attaching to a medical device stand shown in phantom for environmental purposes only and forming no part of the claimed embodiment;

FIG. 4 is a left elevation view of the medical device stand docking head of FIG. 1, with the rear portion for attaching to a medical device stand shown in phantom for environmental purposes only and forming no part of the claimed embodiment;

FIG. 5 is a right elevation view of the medical device stand docking head of FIG. 1, with the rear portion for attaching to a medical device stand shown in phantom for environmental purposes only and forming no part of the claimed embodiment;

FIG. 6 is a top plan view of the medical device stand docking head of FIG. 1, with the rear portion for attaching to a medical device stand shown in phantom for environmental purposes only and forming no part of the claimed embodiment; and,

FIG. 7 is a bottom plan view of the medical device stand docking head of FIG. 1, with the point of connection for interfacing with a medical device stand docking station and the rear portion for attaching to a medical device stand shown in phantom for environmental purposes only and forming no part of the claimed embodiment.

It should be understood that the labels used herein for describing orientation (e.g., front, rear, top, bottom, left, and right) are merely for reference, and the design may be disposed in any manner and still be within the scope of the present invention. The portions of the article in broken lines are shown for illustrative purposes only and form no part of the claimed design.
